UNITED STATES PATENT OFFICE.

FRANK P. DERR, OF BALTIMORE, MARYLAND.

DESIGN FOR A DRINKING VESSEL.

SPECIFICATION forming part of Design No. 26,022, dated September 15, 1896.

Application filed July 31, 1896. Serial No. 601,252. Term of patent 3½ years.

To all whom it may concern:

Be it known that I, FRANK P. DERR, a citizen of the United States, residing at Baltimore, in the State of Maryland, have invented a certain new and useful Design for Drinking Vessels; and I do declare the following to be a full, clear, and exact description of the invention, such as will enable others skilled in the art to which it appertains to make and use the same, reference being had to the accompanying drawing, which forms a part of this specification.

This invention relates to certain new and useful improvements in designs for cups, and especially to a cup having a suitable cover and designed for use as a drinking cup.

My design is clearly illustrated in the accompanying drawing, in which I have shown a perspective view of a cup embodying my design.

The design consists, essentially, of a cup having a substantially cylindrical shape with one side flattened. The upper end of the cup is also flattened, and on the cover is a crow's-foot-shaped member, the body portion of which rises in a forwardly-curved direction, with its free end turned under and slightly upward, while on the rear or convex portion of the body portion is a curved extension, the end of which is also curved downwardly and inwardly. The outline of the periphery of the top of the cup is oval with one straight side and the cover on its oval end is scalloped out.

The handle to the cup has upon its convexed surface a stem with a leaf at its lower end, while at the base of the upper end of the handle are the three points in relief on the curved side of the cup.

What I claim to be new, and desire to secure by Letters Patent, is—

The design for a cup, substantially as hereinbefore described and illustrated in the accompanying drawing.

In testimony whereof I affix my signature in presence of two witnesses.

FRANK P. DERR.
